UNITED STATES PATENT OFFICE

EDWARD J. GULICK, OF ELKHART, INDIANA, ASSIGNEE TO C. G. CONN, LTD., OF ELKHART, INDIANA, A CORPORATION OF INDIANA

HORN

Application filed May 6, 1930. Serial No. 450,252.

This invention relates to valved wind musical instruments, and especially to heavy horns.

The larger types of bass horns are made almost wholly of brass and, when in use, are wholly supported upon the shoulder of the player. Being made of brass such instruments are very heavy, and are not only burdensome to the player when in use, but also the excessive weight thereof is frequently the cause of serious injury to the instrument while in transportation or shipment.

The principal object of this invention is to provide a composite bass, or other, horn of the larger size wherein one or more of the horn sections are made of a relatively light weight metal to materially reduce the weight of the instrument.

Another object of the invention is to provide a composite horn of the larger size wherein the larger sections thereof are made of an aluminum composition to materially reduce the weight of the instrument.

A third object of the invention is to provide a large bass horn wherein the bell and main branch sections are made of an aluminum composition to reduce the weight of the instrument and to eliminate the top-heaviness thereof.

Other objects of the invention are mentioned and described herein.

The preferred embodiment of the invention is illustrated in the accompanying drawing wherein.

Figure 1 illustrates a side elevational view of a bass horn built in accordance with my invention;

Fig. 2 is an enlarged fragmental view illustrating the brace and spacer connection between the bell section and the adjacent brass branch of the instrument;

Fig. 3 is an enlarged fragmental side view of one of the other spacer elements connecting the aluminum main branch of the instrument with the adjacent brass branch;

Fig. 4 is an enlarged fragmental view of the clamp joint between the aluminum main branch and the cooperating end of the brass branch of the horn;

Fig. 5 is a top plan view of one of the elements of one of the spacer connections;

Fig. 6 is a section taken on line 6—6 of Fig. 1; and

Fig. 7 is a section taken on line 7—7 of Fig. 4.

Referring now to the drawings the numeral 1 indicates generally a bass horn of the well known large design, commonly known as a Sousaphone, and which is provided with the usual tubular curvical section 2 upon which the valve action 3 is mounted and which is usually made of brass. The numeral 4 indicates the curvical tubular main branch of the instrument which, according to my invention, is made of some very light weight metal, such as aluminum composition, and which is connected with main section 2 by a ring-like clamp joint 5, as hereinafter described.

The outer end of the main branch section 4 is rigidly connected at 6 in any suitable manner with the usual bell section 7 which, in accordance with my invention is made of aluminum composition, or some suitable light weight metal, to materially reduce the weight of the horn.

The joint 5 may include the cylindrical aluminum, or other suitable light weight metal, thimble element 8 provided with the annular interior socket portion 9 into which the inner end of horn section 4 is telescopically arranged and welded or soldered, said thimble being provided also with the annular exterior shoulder 10 adjacent the socket 9. The outer end of horn section 2 which is connected with branch 4 by the joint 5 is telescopically connected and welded or soldered into an annular or ring-like socket member 11 which is integral with the tubular sleeve 12, said sleeve and socket member being preferably made of brass to enable said welded connection with horn section 2. The thimble 8 of the joint 5 slidably telescopes into the sleeve 12, the outer end of the latter normally snugly engaging the annular shoulder 10 of said thimble which is clamped in that position, as hereinafter described. As stated, the sleeve 12 functions as a clamp and is longitudinally slit at 13 to enable compression

thereof about the thimble 8, such compression being effected by a clamping screw 14 which is loosely mounted in clamping lug 15 and threaded into clamp lug 16, said lugs being welded on opposite sides of said sleeve slit.

To rigidly connect the main aluminum branch 4 with the outer periphery of the brass horn section 2, intermediate the extremities of each horn section, a pair of spacing connector elements 18 and 19 are introduced, said connectors being alike in construction, the details thereof being clearly shown in Figures 3, 5 and 6, and similarly applied to the instrument after the sections 2 and 4 have been joined together at joint 5, as described. Spacer 19 comprises an aluminum pad 20 soldered to aluminum horn section 4 and provided with a rigid boss 21 which is provided with a screw threaded socket. The spacer or connector 19 comprises also, for adjacent horn section 2, a loose brass pad 22 which is provided with a screw stud 23 rigidly mounted therein and projecting therefrom.

The screw stud 23 is adapted to be screwed into the boss 21 of pad 20 until the curvically formed pad 22, initially detached from horn section 2, is brought into the proper relation with section 2 of the horn, whereupon said pad 22 is welded or soldered to the body thereof to effect a permanent union therewith.

The numeral 24 indicates generally a connector-brace unit for permanently uniting the aluminum bell section 7 of the horn with the upper reach of the brass horn section 2, said connector-brace unit including a curvically formed aluminum pad 25 initially soldered to said bell section and provided with a depending post 26 rigid therewith. The unit 24 includes also the curvically formed brass pad 27, initially detached from horn section 2, which is provided with the upward stud 28 rigid therewith, said stud being screw threaded at its outer upper end 29, for screw thread connection with the threaded aperture 30 in the post 26 prior to welding or soldering the pad 27 to the brass body 2 of the horn.

In thus constructing a large bass horn of both aluminum and brass I reduce the weight of an all brass instrument fully 35%. Also, I practically eliminate the top-heavy feature which exists in all such brass horns and which is very objectionable of itself.

I claim:

1. A wind musical instrument of the character described which comprises a plurality of tubular curvical sections, one or more of said sections being made of relatively light weight metal and including exterior spacer members joining two or more of said instrument sections, said spacer members being a

composite of relatively light and heavy weight metal.

2. In a wind musical instrument of the character described which is provided with a valve action supporting section and a main branch section, a bell section of relatively light weight metal operatively connected with said main branch section, and a spacer member joining said bell section with said valve action supporting section, said spacer member being a composite of relatively light and heavy weight metal.

3. A wind musical instrument of the character described comprising a valve action supporting section made of relatively heavy weight metal, and coacting main branch and bell sections which are made of a relatively light weight metal, and exterior spacers connecting said main branch and valve action sections, said spacers being composite members and including a part thereof which is made of relatively light weight metal.

4. In a wind musical instrument of the character described which is provided with a valve action supporting section and a main branch section, a bell section of relatively light weight metal operatively connected with said main branch section, and an exterior spacer connecting said bell section with the valve action section, said spacer comprising a pair of opposed pads connected together by screw means.

5. In a wind musical instrument of the character described which is provided with a valve action supporting section and a main branch section, a bell section of relatively light weight metal operatively connected with said main branch section, and an exterior spacer element rigidly connecting said bell and valve action sections, said spacer comprising a pair of opposed pads, one of which is made of relatively light weight metal, said pads being rigidly connected together by screw means.

6. A wind musical instrument of the character described comprising a valve action supporting section made of relatively heavy weight metal, and coacting main branch and bell sections made of relatively light weight metal, and exterior spacers connecting said main branch and valve action sections, each of said spacers comprising a pair of opposed pads connected together by screw means.

EDWARD J. GULICK.
